UNITED STATES PATENT OFFICE

EDWARD S. HALSEY, OF MIAMI SHORES, FLORIDA

ROOM TEMPERATURE REGULATING AIR VALVE

Application filed February 6, 1930. Serial No. 426,287.

The invention relates to heating systems of the general type in which the radiators are supplied with steam of less than atmospheric pressure and are vented into suction pipes and concerns particularly valve mechanism having a valve, controlling air to the vent of the radiator, controlled by a room thermostat whereby the supply of steam to the radiator is regulated.

10 The invention consists in the features and combination and arrangement of parts hereinafter described and particularly pointed out in the accompanying claims.

In the drawings

15 Fig. 1 is a vertical sectional view of one form of the invention.

Fig. 2 is a similar view of another form of the invention.

20 Fig. 3 is a diagrammatic view of the system embodying the invention.

In these drawings, 1 indicates the radiators to which steam is supplied by the pipes 2 from a boiler 3. At 4 is shown the suction pipe leading from the vent end of the radiators, at which end my improved valve mechanism is employed, it being located at and connected with the vent, as will be presently described.

25 The suction pipe 4 leads to any suitable form of aspirator 5, operated by water under pressure introduced to said aspirator through a pipe 6 under control of a valve 7. The aspirator discharges to any suitable drain or sewer. The steam boiler is of any ordinary form controlled by a damper 8 and sylphon bellows regulator 9.

30 The valve constituting my invention comprises a casing 10 having a nipple 11 by which attachment to the usual vent opening of the radiator can be made. The casing may be made in two parts, the upper part 12 being screw threaded onto the block or partition member 13, to which the lower part 10 is also screw threaded. This partition has a 35 central port 14, controlled by a valve 15 connected by a rod 16 with an arm 17 extending through an opening 18 in the valve casing and connected with a suitable form of thermostat indicated generally at 19, and shown in detail in an application of even date here- 40 with.

There is a passage 20 extending from the port 14 to the suction pipe. The outlet of this passage is adjustable by a screw pin 21. The port 14 through the partition 13 is also controlled by a valve 22 connected with a 45 hollow float or expansible unit 23 in the lower part of the casing. This float rests upon an adjustable pin 24 by which the initial position of the float valve may be determined.

This unit 23 contains alcohol vapor so that 50 the upper wall bearing the valve point 22 will expand under heat and said point will close the port 14. This will take place when steam begins to flow through the attachment from 55 the vent end of the radiator. Furthermore, the float will rise when water enters the valve casing from the radiator vent and thus the port 14 will be closed.

We will suppose that the radiator and 60 room are cold. The bi-metal thermostat is 70 so wound that valve 15 will be closed. The suction through pipe 4 will draw steam into the radiator and the air and steam vented from the radiator will pass to the pipe 4 through the central port 14 in disc 13 and 75 the minute passage 20.

Now when the room temperature has raised 80 to the prescribed degree, the thermostat will open valve 15 and atmospheric air will pass 85 into the device through opening 18 and thence through port 14 to the radiator through the vent pipe 11 thereof. This will be due to the subnormal pressure within the radiator. Some air will pass through the narrow passage 20 under the suction in pipe 4 but the main body of air will pass into the 90 radiator, and this air will back up in radiator and check the inflow of steam, as the system operates with steam slightly below atmospheric pressure.

The opening 14 at the center of the disc 95 13 may be closed also by the expansible float valve 22 to prevent escape of steam or water. When the room cools off below the temperature desired, the room thermostat will lower the arm 17 and close the valve 15, thus cutting off any further inlet of air through the opening 18 and then the suction through pipe 4 will act to vent the radiator through 100 nipple 11, thence past the valve 22 and

through passage 20. Steam will now enter the radiator and the temperature of the room will rise.

The form of the invention shown in Fig. 5 2 is like that of Fig. 1, except that the valve 15a controls a port at 25 for the supply of air. This valve 15a is operated by a room thermostat so wound that it will rise when the room cools and close air inlet 25. The suction 10 from pipe 4 now draws through ports 26 and 27 past the elevated valve 15a, now closing air inlet 25, thus drawing steam into the radiator.

When the temperature of the room rises, 15 then valve 15a lowers and opens port 25 for access of air, which backs up through port 26 and nipple 11 to displace the steam in the radiator and cause its temperature to lower. At 20 the same time valve 15a will cut off communication between port 27 and the port 25 and also between pipe 4 and the port 26, so that the suction will be stopped at this point.

In both the above forms the steam is maintained below atmospheric pressure.

25 A float valve 22, 23 similar to that previously described is employed in this form of the invention. When this valve is down and open, it leaves a comparatively small orifice.

The port 20 is restricted in diameter relative to the diameter of the port 14, which is, say, five times as great, so that when valve 15 is open, it dominates in the control of the air and the air will pass through the port 14 into the radiator despite the suction in pipe 4. It is understood that the apparatus works under about one pound of suction. The passage 20 can be cleaned by removing the screw plug 2.

Instead of mounting the valve mechanism 40 at that end of the radiator at which the vent is located, I may mount the valve on the opposite end of the radiator, i. e., the steam inlet end, but connect it up with the vent by a suitable pipe extending along the radiator 45 from the vent end to the inlet end. By locating the valve mechanism with its thermostat at or near the inlet end of the radiator, there may be less liability to variation in the action of the thermostat, because the section of 50 the radiator at the inlet end is more uniformly heated than is the last section where the vent is located. This last section at times may be totally devoid of heat and at other times it may be heated and the air currents therefore at this end of the radiator are subject to considerable variation which might induce undesired actions by the thermostat.

At the inlet end of the radiator, however, because the first two or three sections of the 60 radiator are usually heated, when the radiator is in service at all, the air currents will be more uniform and the room thermostat will not be subject to undue variation.

The thermostat is supported by arms 19a 65 from a block of heat insulating material such

as bakelite, which is mounted on the frame and casing 12, so that the whole organization constitutes one unit to be mounted on or removed from the radiator as one body, by means of the nipple 11. The heat insulating 70 block 19b is interposed between the casing and the thermostat and insulates the same against both conducted and radiated heat from the radiator.

I claim:

1. In combination with a radiator, and a suction pipe, a valve mechanism between the atmosphere and the radiator, comprising a valve for closing a passage between the radiator and atmosphere, a room thermostat for 80 operating said valve, said suction pipe being in constant communication with said passage between the valve and the radiator through a port of restricted capacity in respect to the 85 passage first mentioned, to draw upon the radiator when the valve is closed and to permit access of atmospheric air through said passage to the radiator to displace the steam when said valve is open, substantially as described.

2. In combination with a radiator and suction pipe, a valve mechanism between the atmosphere and the vent of the radiator, and comprising a double acting valve having a seat at each side thereof, said valve when on 95 one seat controlling a passage between said vent and atmosphere and when on the other seat controlling a passage leading to the suction pipe from said vent, a room thermostat connected to the valve for closing the passage 100 first mentioned when the room temperature falls, leaving the second passage open for the suction to draw steam into the radiator, said thermostat operating the valve when the room temperature rises to close the passage 105 to the suction pipe and open the air passage for admission of air to the radiator through the vent, substantially as described.

3. A regulator for radiators comprising a frame member having a head or partition 110 provided with a port for the admission of atmospheric air, and having a connection to the vent of the radiator by which atmospheric air entering through said port may reach the radiator, a suction pipe connected 115 with a port in said head or partition to draw upon the radiator through the port first mentioned, a valve controlling the admission of air through said port, and a room thermostat controlling the valve, substantially as described.

4. Radiator valve mechanism comprising a casing having means to connect with the vent of the radiator a partition in said casing, a port extending through said partition for passage of atmospheric air to the vent, a suction port in said partition having communication with the vent by way of the port first mentioned, suction pipe connected with the suction port, a valve controlling the passage of 120

air to and from the vent through the first mentioned port and a room thermostat controlling said valve, substantially as described.

5. Radiator valve mechanism according to
5 claim 4 having a float valve within the casting controlling said first mentioned port to prevent the escape of steam or water either to atmosphere or to the suction pipe.

6. Radiator valve mechanism according to
10 claim 4 in which the valve is double acting, with a valve seat at opposite sides thereof, said valve when on one seat closing the suction connection and opening the communication from said first mentioned port to atmosphere and when on the other seat opening the suction port and closing communication between said first mentioned port and atmosphere.

7. In combination, a casing having means
20 for attachment to the vent of a radiator and having a port communicating said vent with atmosphere, a valve controlling said port, a thermostat controlling said valve, a suction pipe, said casing having a passage communicating said suction pipe with the vent, said passage being of less capacity than the passage first mentioned so that when the valve is open air will go to the radiator despite the suction action tending to oppose it.

30 8. Apparatus according to claim 1 in which the restricted port is elongated to provide a relatively fixed resistance and an adjustable clean-out means in line therewith, substantially as described.

35 In testimony whereof, I affix my signature.
EDWARD S. HALSEY.
